LINE TIGHTENER

Marion E. Lawrence, Long Beach, Calif., assignor
to Harmon E. Farr, Long Beach, Calif.

Application January 29, 1946, Serial No. 644,075

2 Claims. (Cl. 254—161)

1

This invention relates to line tightening and holding devices and particularly to an improved device for adjustably tensioning lines, ropes, cables and the like to maintain them taut.

One object of the present invention is to provide a line tensioning and holding device having a rotary winding member adapted to receive the end of a line and to be readily rotated to wind up the line and apply the desired degree of tension thereto.

Another object is to provide a line tensioning and holding device having automatic means for retaining the rotary member in adjusted position to prevent retrogressive movement thereof and so maintain the line taut.

Another object is to provide a device of the type indicated comprising a frame member adapted to be mounted against a line support, a winding member rotatable on said frame and to which an end of a line is secured, and angularly related handles slidably carried by said winding member for rotating the winding member to wind the line thereon, said handles being adapted to automatically and successively engage said support to prevent reverse rotation of the winding member.

Another object is to provide a device of the type indicated adapted for use in tensioning various types of lines and cables and one which may be mounted in several ways with or without the use of separate fastening means.

Another object is to provide a device of the type indicated which may be applied to use with its rotary winding member arranged either horizontally or vertically so that lines may be tensioned between vertical posts or horizontal supporting arms.

Another object is to provide a device of the type indicated which is composed of a minimum number of parts adapted for economical manufacture and convenient assembly without the use of screws, rivets or other extraneous parts, and one which is proof against derangement and getting out of order.

Further objects of the invention are set forth in the following part of the specification which describes the line tightening and holding device as embodied in a preferred form of construction, by way of example, and as illustrated by the accompanying drawing. Referring to the drawing, which is for illustrative purposes only,

Fig. 1 is a perspective view of a line tightening and holding device embodying the novel features of my invention;

Fig. 2 is a side elevational view of the device

2

showing it applied to a wall or other flat surface for tensioning a line between the wall and a line support remotely spaced therefrom;

Fig. 3 is a part-sectional front elevational view of the device showing the means for mounting the rotary line-winding member and indicating the manner in which the end of the line is attached to said winding member; and

Fig. 4 is a cross-sectional view of the device, taken on the line 4—4 of Fig. 3, showing the device applied to use in tensioning a line between a tubular support and a point removed therefrom.

In supporting ropes, cables and the like, such as those used for clotheslines, tennis and badminton net lines, arbors and fences, and radio antennae it is desirable to tension said lines to maintain them taut. Various devices have been employed for tensioning such lines, one commonly used type consisting of a manually rotatable drum or reel to which one end of the line is attached to be wound up thereon when the drum is rotated. In such devices a pawl and ratchet means is usually provided for preventing reverse rotation of the drum and sagging of the line. In another similar wind-up device, the winding drum is automatically rotated by means of a helical wind-up spring to maintain the line taut. Such prior line tensioning devices are complicated in construction, being composed of a relatively large number of parts which are subject to wear and breakage. When such devices are used out-of-doors and exposed to the weather their parts soon rust and deteriorate to render the devices unsuitable for use. Moreover, prior devices of these types are unsuited for use with steel cables, such as are used for radio antennae, electric fences and clotheslines and which require a relatively high degree of tension to maintain them taut. Furthermore, these devices are limited in use inasmuch as they must be secured to a flat surface and cannot be fastened to circular posts or other line supports having irregular contours.

To overcome the faults of these devices, it has been the practice to use turnbuckles for tensioning cables and other lines. While turnbuckles provide efficient means for tightening most lines, they occupy space in the line which could otherwise be utilized to advantage and when the line has stretched to a length which cannot be readily taken up by the turnbuckle it is the usual practice to disconnect the turnbuckle from the line, sever a length from the line and again attach the end of the line to the eye of the turnbuckle. A further disadvantage of the conventional clothes-

line is that it is not possible to tension the line to a desired degree of tension without disconnecting the turnbuckle and severing a length of line. The use of turnbuckles is also disadvantageous in that they are subject to fatigue and failure under repeated tensioning and relaxation of the line.

line turnbuckles is that they provide, at the most, only several inches of take-up for the line. As is well known, turnbuckles are located in and form, in effect, a part of the line and thus it is usually necessary to provide screw-eyes or similar fastening means which are fastened to the line supporting structure and to which one end of the turnbuckle, or a length of cable extending from the turnbuckle, is secured.

The present invention was conceived as a means for obviating the faults of previously used devices. The improved device comprises, in general, a substantially U-shaped frame member adapted for attachment to a line support and having a base and side members projecting from said base. A cylindrical winding member is rotatably mounted in the side members and employed for winding up and tensioning the line which is attached thereto. One or more handles are slidably mounted on the winding member to facilitate manual rotation thereof, said handle or handles being adapted to engage against the line support or against means on the frame member to retain the winding member in any position of adjustment.

Referring to the drawing, my improved line tightening and holding device comprises a substantially U-shaped frame member 5 having a base portion 6 which is recessed on one side to provide spaced pads or feet 7 and having spaced side members or arms 8 and 9 projecting from the opposite side of the base portion. The base portion 6 of the frame member 5 is provided with a centrally disposed rectangular opening 10, and a pair of holes 11 for receiving mounting screws or bolts. The side members 8 and 9 of the frame member 5 have aligned bearing apertures 12 for rotatably receiving a winding member 15.

The winding member 15, which is shown most clearly in Fig. 3, comprises a cylindrical rod or shaft having bearing portions 16 rotatably mounted in the bearing apertures 12 of the frame member 5 and having a central reduced portion 17 around which the wire cable or other line 18 is adapted to be wound. The ends 18 and 20 of the winding member 15 project laterally beyond the side members 8 and 9 of the frame 5 and one of the ends 19 is enlarged slightly in diameter, thereby providing a shoulder 21 which abuts the side member 8 of the frame. A hole 24 extends through the member 15 from the reduced portion 17 to the projecting end 19 at an angle to the axis of the member 15, the hole serving as the means for attaching the end of the cable or line 18 to the winding member in a manner to be later explained.

Holes 25 extend diametrically through the projecting ends 19 and 20 of the member 15, at right angles to each other, for the purpose of receiving operating rods or handles 27 and 28. The handles 27 and 28 are dapped or flattened adjacent their ends, after being inserted through the holes 25, to provide projections 29 for retaining the handles in place while permitting sliding movement thereof in the holes 25. It will be seen by reference to Fig. 3 that the rotary winding member 15 is held against axial displacement in one direction through the engagement of its shoulder 21 which abuts the side member 8 of the frame 5, and against axial movement in the opposite direction by the handle 28 which is positioned adjacent the side member 9 of the frame.

The improved line holding and tensioning device is applied to use in the manner next explained. Assuming that a line or cable is to ex-

tend between a post or other support, not herein shown, and the side of a building or other flat object, represented by the dot-and-dash lines 32 in Figs. 1 and 2, the device may be mounted 5 against the outer surface of the building and fastened in place by screws 33 passing through the holes 11 of the base 6 and screwed into the side of the building. With the device thus secured in place, the end of the line 18 is threaded 10 through the hole 24 of the winding member 15 and the end of the line which projects through the hole 24 is preferably left intact for future use but, if desired, it may be cut off and the line tightened as next explained.

To wind up the line 18 and apply tension thereto, the handles 27 and 28 are successively turned to rotate the winding member 15 to cause the line to be wound on its central portion 17. It will be observed from the drawing that the distance between the side of the building 32 or other relatively flat support and the axis of the winding member 15 is considerably less than the length of the handles 27 and 28 so that each handle may be successively turned through approximately ninety degrees to wind a quarter turn of the line on the winding member 15. Stated another way, as each handle is turned from a substantially vertical to a substantially horizontal position, the other handle will be moved from a substantially horizontal to a substantially vertical position, each handle sliding in its hole 25 to permit such turning movement. As each handle 27 or 28 approaches a substantially vertical position it will slide downwardly in its hole 25 under the influence of gravity so that one of the handles will always be in a depending position to adapt it to engage against the wall 32, or other line support, to prevent reverse rotation of the winding member 15 and unwinding of the line 18.

Fig. 1 illustrates the line 18 attached to the winding member 15 by initially winding it thereon in counter-clockwise direction, it being understood that the other end of said line is suitably joined to another remotely spaced line support, not herein shown. It will be observed that one handle 27 extends substantially horizontally from the winding member 15 while the other handle 28 extends downwardly from the member in position to cause its lower end to engage against the wall 32 or other line support to prevent rotation of the winding member in clockwise direction which would cause the line 18 to unwind therefrom. To tension the line 18, the handle 28 is grasped by the operator and turned through an angle of approximately ninety degrees to wind a quarter turn of the line 18 upon the winding member 15, whereupon the other handle 27, which has been turned to substantially vertical position will slide downwardly in its bearing hole 25 under the influence of gravity to the position shown by full lines in Fig. 2. The handle 27 is then used as the means for rotating the winding member 15 through the next ninety degrees and as this handle is moved to a substantially horizontal position the other handle 28 will approach a substantially vertical position and slide downwardly in its bearing hole 25. Coiling of the line 18 upon the winding member may be continued by alternately turning the handles 27 and 28 and as each handle is turned, the other handle will be automatically moved into a position wherein its lower end engages the line support 32 to prevent reverse rotation of the member 15 as shown by the

full lines in Fig. 1 and the dot-and-dash lines 35 in Fig. 2. It is thus seen that the handles 27 and 28 act automatically and positively to check rotation of the winding member 15 to maintain the proper tension and prevent unwinding of the line 18. If the line stretches during use it may be tightened by rotating the winding member in the manner above explained. On the other hand, if it is necessary to relieve the tension applied to the line 18 or to remove the line from the winding member 15 the member may be rotated in reverse direction by alternately sliding the handles 27 and 28 upwardly in their bearing holes 25 and turning them in clockwise direction.

When the device is to be used on a tubular line support such as that indicated at 36 in Fig. 4, holes 37 are drilled through the support and the line 38, indicated by dot-and-dash lines, threaded through the holes. The support 36 may constitute a vertical post or the crossarm of a clothes-line support and in either case the line tightening device is placed against the opposite side of the support with its pads 7 engaging the periphery thereof as shown in Fig. 4. The line 38 may then be passed through the rectangular opening 10 and attached to the winding member 15 in the manner previously explained. As the member 15 is rotated in counter-clockwise direction, as viewed in Fig. 4, the line 38 will be coiled thereon to be tensioned and the handles 27 and 28 will successively and automatically engage against the periphery of the tubular support 36 as indicated by the dot-and-dash lines 39 in Fig. 4 to prevent reverse rotation of the member and unwinding of the line. It will be noted from the above that when the line tensioning device is applied to use on a tubular line support the tension of the line serves to hold the device in place and thus the employment of screws, bolts or the like is unnecessary. It is also apparent that the frame member 5 will be shifted circumferentially of the tubular line support 36 due to tension in the line 38, as shown in Fig. 4, so that greater support is provided at the side of the device opposite to the point of winding to counteract the torsional force applied against the handles 27 and 28 during the winding operation. The device may be used in a similar manner when a line is to be secured to the side wall of a building by first drilling a small hole in the side wall and inserting the line through the hole. The device is then placed against the interior of the side wall and the end of the line attached to the winding member 15, after which the line may be wound on the member by alternately operating the handles 27 and 28 in the manner previously explained. Thus, the line tightening device may be applied to use without the necessity of fastening it in place by means of screws, bolts or the like.

It will be observed from the foregoing that my invention provides an extremely simple, yet highly efficient line tensioning and holding device. The device is composed of a minimum number of parts with the frame member and winding member adapted to be manufactured as die-castings and the operating handles made from rod stock. The parts are assembled without the use of screws, rivets or other extraneous parts liable to become broken to render the device useless. The die-cast parts are resistant to rust and corrosion and the operating handles are suitably plated so that the device may be used out-of-doors without danger of rusting. The device is exceptionally strong and durable and especially adapted for

use in tightening wire cables which are usually subjected to considerable tension to maintain them taut, it being noted that the rotative force applied to the winding member through the operating handles is sufficient to exert considerable pull on the line.

As a particular feature of improvement, the present invention provides a very efficient means for retaining the winding member in adjusted position to prevent reverse movement of the winding member and unwinding of the line therefrom. By utilizing the operating handles for this purpose the necessity of providing complicated pawl and ratchet mechanism or similar rotation checking devices, subject to wear and breakage, is entirely avoided. However, it is within the concept of my invention to provide suitable stop-lugs or pins on the side arms 8 and 9 of the frame member 5 which are engageable with the handles 27 and 28 to prevent reverse rotation of the winding member 15. The device is extremely easy to operate and when the line becomes stretched in use, it may be re-tightened by merely turning the operating handles. Thus, it is unnecessary to disconnect the line from the device and cut a length therefrom. Moreover, the device takes up very little of the length of the line when interposed between the line supports and none of the length of line when applied against the reverse side of a line support so that the maximum length of line may be utilized for the purpose for which it is intended. In most cases the device may be installed without screws or other fastening means and thus may be easily and quickly applied to use.

My improved line tightening device may be used as a means for tightening clotheslines, tennis and badminton net lines, the wires of arbors, wire fences, radio antennae, guy wires, and other lines or straps or flexible members wherein a relatively high degree of tension is desirable, and, accordingly, wherever I use the term "line" herein I intend to cover any such flexible member.

It is also to be noted that the drawing shows a commercial form of my line-tightening device in approximate full size, and that the reduced portion 17 of the winding means 15 in effect constitutes a drum of substantial circumference. This permits a relatively great length of line to be wound thereon, which is an advantage over conventional turnbuckles. For example, several feet of relatively heavy gauge wire may be wound on the winding means 15, to provide sufficient take-up for even relatively long lines of stretchable material, such as soft galvanized wire.

While the improved line-tensioning and holding device has been herein shown and described as embodied in a preferred form of construction by way of example, I do not intend to be limited to the specific disclosure contained herein since various changes, modifications, and substitutions may be incorporated in the exemplary embodiment disclosed without departing from the spirit of the invention, and I hereby reserve the right to all such changes, modifications, and substitutions as properly come within the scope of my appended claims.

I claim as my invention:

1. A device for tensioning a line between a line support and a point remote therefrom, comprising: a U-shaped frame member including a mounting portion adapted to be disposed against the line support, and spaced arms projecting from said mounting portion, said arms being provided

with circular bearing apertures; a drum member rotatable in said apertures with its ends projecting beyond said arms, one of said ends having an enlarged portion, and each of said ends having a diametrical hole, said drum member having a hole for receiving the end of said line to secure said line thereto; and elongated handle members slideable in said diametrical holes and provided with means for preventing their withdrawal from said diametrical holes, said handle members being alternately slid downwardly in the diametrical holes under the influence of gravity during rotation of said drum member to engage against the line support to prevent reverse rotation of said drum member, said enlarged portion at one end of said drum member and the handle member at the other end of said drum member being adapted to automatically engage said arms to retain said drum member in said bearing apertures.

2. A device for tensioning a line between a substantially circular line support and a point remote therefrom, comprising: a U-shaped frame member including a mounting portion adapted to be disposed against the line support and having pads engageable against the periphery of the line support, and spaced arms projecting from said mounting portion, said arms having aligned, circular bearing apertures; a drum member rotatable in said apertures with its ends projecting beyond said arms, one of said ends having a head and each of said ends having a diametrical hole,

said drum member having a hole for receiving the end of said line to secure said line thereto; and elongated handle members slideable in said diametrical holes and provided with projections at their ends for preventing their withdrawal from said diametrical holes, said handle members being alternately slid downwardly in the diametrical holes under the influence of gravity during rotation of said drum member to automatically engage against the line support to prevent reverse rotation of said drum member, said head at said one of said ends of said drum member engaging against one of said arms to prevent longitudinal movement of said drum member in one direction, and the handle member at the other end of said drum member engaging against the other of said arms to prevent longitudinal movement of said drum member in the opposite direction.
